(57) **CLAIM**

The ornamental design for a driving head for power tool, as shown and described.

DESCRIPTION

FIG. 1 is a perspective view of a driving head for a power tool showing my new design;

FIG. 2 is a front elevational view thereof, it being understood that the design is uniform about its circumference; FIG. 3 is a left side elevational view thereof;

FIG. 4 is a right side elevational view thereof; and,

FIG. 5 is a perspective view thereof, the power tool head and the screw driver bit depicted by means of broken lines being for illustrative purposes only and forming no part of the claimed design.
